United States Patent Office

Des. 183,150
Patented July 1, 1958

183,150

BADGE OR SIMILAR ARTICLE

Alexander E. Ulmann, New York, N. Y.

Application August 30, 1956, Serial No. 42,797

Term of patent 14 years

(Cl. D29—2)

~~FIG. 1.~~

~~FIG. 2.~~

Fig. 1 is a front elevational view of a badge or similar article, showing my new design; and

Fig. 2 is an edge elevational view thereof.

The back of the article is substantially plain.

The dominant features of my design reside in the portions shown in full lines in the drawing.

I claim:

The ornamental design for a badge or similar article, as shown and described.
